H. WINDIBANK.
APPARATUS FOR THE ATTACHMENT OF ELECTRIC WIRES TO TERMINALS.
APPLICATION FILED DEC. 21, 1918.

1,320,594.

Patented Nov. 4, 1919.

Inventor,
Henry Windibank
by Robert W. Jenner.
Attorney.

UNITED STATES PATENT OFFICE.

HENRY WINDIBANK, OF CROYDON, ENGLAND, ASSIGNOR TO ARTHUR TAYLOR TREGLOWN, TRADING AS L. TAYLOR & CO., OF LONDON, ENGLAND.

APPARATUS FOR THE ATTACHMENT OF ELECTRIC WIRES TO TERMINALS.

1,320,594.

Specification of Letters Patent.

Patented Nov. 4, 1919.

Application filed December 21, 1918. Serial No. 267,810.

To all whom it may concern:

Be it known that I, HENRY WINDIBANK, a subject of the King of Great Britain and Ireland, residing at Croydon, England, (whose post-office address is 29 Pemdevon road, Croydon, in the county of Surrey, England,) have invented certain new and useful Improved Apparatus for the Attachment of Electric Wires to Terminals; and I do hereby declare the following to be a full, clear, and exact description of the invention, such as will enable others skilled in the art to which it appertains to make and use the same.

This invention consists in improved means for attaching electric wires to terminals, and has for its object to provide simple, and efficient means whereby such wires can be quickly and effectively connected to the terminals and quickly removed therefrom, without the necessity of employing and manipulating the usual nuts by which such wires have heretofore been secured to the terminals. The means according to this invention can be readily applied to existing terminals, the usual clamping nuts of which can be dispensed with.

The invention consists principally in a clip formed of suitable metal with spring action and adapted to be simply passed or moved on to a terminal or terminal screw of usual or suitable type so as to embrace the terminal and thus attach the electric wire or conductor to the terminal, the said clip being formed or provided with any suitable means for easily connecting the electric wire to the clip. Further according to this invention the clip is preferably formed with parts or provided with means adapted to engage or interlock so that by a simple manipulation, as by pressing the parts by the finger and thumb, or by a simple action similar to the action of turning a key, or to the action of winding a clock, the clip is effectively tightened on the terminal and the said parts or means are caused to engage and thus form a catch for retaining the clip in its tightened condition on the terminal.

Further according to this invention, in one embodiment thereof, the above mentioned clip consists of a piece of suitable spring or resilient wire—such for instance as piano wire—a portion of which, intermediate the ends, is formed into a coil like a spiral spring, and to the straight or un-

coiled portion of the wire at one end of the coil a small tube or socket is attached for receiving the end of the conducting wire or wires, the other uncoiled or straight portion of the wire at the other end of the coil being for a suitable part of its length from the end turned upwardly (or bent at or approximately at right angles to the straight portion) and suitably bent to form a catch which, by simple manipulation can be caused to engage with or against the aforesaid small tube thereby tightening the coil on the terminal screw or pin and at the same time maintaining it in its tightened condition. Further by simple pressure of the thumb or finger on, or by a simple manipulation of, the aforesaid upturned part of the wire of which the clip is formed the clip can be quickly disengaged from the small tube or wire connector thereby loosening the coil on the terminal so that the clip with wire connector and electric wire attached thereto can as a whole be quickly removed from the terminal screw by simply drawing the coil off the screw.

The invention further consists in a clip adapted to be easily and quickly applied to a terminal screw or pin, and comprising a part to which the electric conductor can be easily and quickly secured and means adapted to be quickly and easily manipulated so as to tighten the clip on the terminal screw, all substantially as hereinafter described and illustrated in the accompanying drawings.

In the drawings:—

Figs. 1, 2 and 3 are, respectively a side elevation, an end elevation and a plan view of a clip comprising a wire connector and tightening means, according to one embodiment of the invention.

Figs. 4 and 5 are, respectively, an elevation and a plan of a sparking plug with the clip on the terminal screw and show the end of an electric wire or conductor secured to the clip.

Figs. 6 and 7 are plan views of an alternative construction of clip according to this invention, these figures respectively showing the clip in its open and in its closed condition. Fig. 8 is a side elevation of this clip in its open condition.

Like reference numbers indicate corresponding parts in the several figures of the drawings.

1 is the hereinbefore mentioned coil of suitable wire—for instance piano wire coated with copper—the part 1^a of the wire extending from one end of the coil a suitable distance to receive the electric wire connector 2 which is secured to the part 1^a in any suitable manner; from the other end of the coil the part 1^b of the wire of which the coil is made extends to a suitable distance from the coil and is bent upwardly as at 1^c this latter part being itself bent laterally and suitably shaped, including the loop head 1^d, to form a catch. As clearly shown in Fig. 3 the parts 1^a and 1^b make a suitable angle with each other so as to provide the desired spring action of the catch. Instead of the angle shown in Fig. 3 the parts 1^a, 1^b might, in the open condition of the catch, lie at right angles to each other. As clearly shown in Fig. 2 the part 1^c is bent laterally so as to provide a curved part or recess 1^e, adapted to take against or to partially embrace the wire connector 2 when the clip is in its closed or tightened condition as shown in Figs. 4 and 5.

The wire connector 2 as shown consists of a small tube or socket of suitable metal adapted to receive the electric wire or conductor as shown in Figs. 4 and 5 in which 3 is the stranded wire of the electric conductor 4 this wire being passed into the tubular connector 2 and suitably secured therein, for instance by pressing the metal of the connector 2 tight on the wire 3 by means of a pair of pliers or by a blow from a hammer. As an additional security against the wire 3 becoming detached from the connector 2 the several wires of the stranded conductor 3 may be turned over the end of the connector 2 as shown at 3^a Figs. 4 and 5.

In the example shown the connector 2 is made of a small piece of suitable sheet metal, for instance copper, bent or otherwise suitably formed into a small tube one edge of the piece of metal being first bent over to form a tubular housing 5 for the part 1^a of the wire of coil 1, the part of the connector 2 forming the housing 5 being slipped on to the said part 1^a and preferably pressed or pinched tight on the wire 1^a the end of which is preferably bent over the end of the connector 2, as clearly shown in the drawings, in order to insure the connector 2 being retained in, effective connection with the clip 1.

6 is the usual terminal screw of the sparking plug shown in Figs. 4 and 5.

7 is a small pointed tongue cut in one side of the connector 2 and having its point bent inwardly so that when this tongue is pinched or pressed inwardly its point will enter or engage the wires of the conductor 3. This tongue is, however, not essential for securing the conductor 3 in the connector 2 and may be dispensed with.

As shown the clip or coil forms a relatively deep sleeve or collar adapted to embrace the terminal 6 for a substantial portion,—as shown the major portion,—of its length and thus tends to effective contact being made between the clip and the terminal and also insures a more rigid attachment of the clip to the terminal.

The clip, comprising the coil 1, is placed on the terminal screw 6 by being simply passed over the end of the screw, and the clip is tightened on the screw 6 by simply pressing,—by means of the finger and thumb,—the parts 1^a and 1^b, 1^c of the wire of which the clip is made toward each other, with a turning action, similar to the action of turning a key or the action of winding a clock, until the head 1^d has been passed, from the position shown in Figs. 1, 2 and 3, to the opposite side of the connector 2, i. e., to the position shown in Figs. 4 and 5, and the curved or recessed part 1^e of the catch contacts with or partially embraces the side of the connector 2 with the head 1^d extending more or less across the connector 2; by this action the coil or clip 1 is tightened on the terminal screw 6 so as to effectively hold the clip on the terminal, and to make effective contact between the clip and the terminal. For quickly removing the clip 1 with wire connector 2, so as to disconnect the electric conductor 3 from terminal 6, the catch 1^b, 1^c, 1^d, is disengaged from the connector 2 by a similar action to that above described but in the reverse direction.

Referring now to the alternative form of clip shown in Figs. 6, 7 and 8 of the drawings in this case the clip is made of a piece or strip of suitable spring metal so formed as to provide the loop shaped end marked 100 forming a sleeve or collar adapted to be passed on to the terminal screw or pin so as to embrace same; the part 10^a of the clip is set outwardly so that it lies at a suitable angle to the straight part 11 on the end 105 of which is fixed, for instance by pinching or clamping a part 12 of suitable metal comprising a small tube or socket 13 adapted to receive the end of the electric wire or conductor. 14 is a catch, similar to a purse catch, pivoted at 15 on the straight part 11 and adapted to readily slip over or engage the parts 10^a and 11 when the part 10^a is pressed against the part 11.

As shown in Fig. 8 that portion of the straight portion 11 of the clip on which the part 12 with socket 13 is mounted is somewhat narrower than the part on which the catch 14 is mounted. The part 12 with tube or socket 13 is preferably made of 125 suitable soft or pliable metal, such for instance as copper, so that when the end of the electric wire is inserted in the tubular part 13 the latter can be pressed or pinched tight on to the wire.

Assuming the loop or collar 10 to be passed on to the terminal screw 6 (Fig. 4), in order to tighten the clip on the terminal, and to maintain it in its tightened condition thereon, it is only necessary to press the part 10^a up to the part 11 (or to press these parts together) and to press down the catch 14 which will tightly embrace the parts and hold the clip in its closed condition. By simply raising the catch 14 the clip is opened or loosened and can be quickly slipped off the terminal.

While the form or embodiment of my invention which I prefer is that hereinbefore described with reference to and shown in Figs. 1 to 5 inclusive of the accompanying drawings, I wish it to be distinctly understood that a terminal clip with wire connector attached and formed as or provided with parts forming a spring catch for tightening the clip on the terminal might be made otherwise than as shown in the accompanying drawings without departing from my invention.

What I claim as my invention and desire to secure by Letters Patent is:—

1. A fastening device, comprising a contractile tubular socket adapted to encircle an electric terminal, said socket being formed of a helical coil of spring wire hav-

ing a laterally projecting arm at one end and having an angle-shaped catch at the other end which overlaps the said arm and which is adapted to be sprung back and forth from one side of it to the other to operate the contractile socket, and means for connecting an electric wire to the said arm independently of the said catch.

2. A fastening device, comprising a contractile tubular socket adapted to encircle an electric terminal, said socket being formed of a helical coil of spring wire having a laterally projecting arm at one end and having an angle-shaped catch at the other end which overlaps the said arm and which is adapted to be sprung back and forth from one side of it to the other to operate the contractile socket, and a connecting device having two tubular portions one of which is secured over the said arm and the other adapted to be secured to an electric wire independently of the said catch.

Dated this 26th day of November, 1918.
In testimony whereof I affix my signature, in presence of two witnesses.

HENRY WINDIBANK.

Witnesses:

W. H. LEWERS,
I. G. WEST.

It is hereby certified that Letters Patent No. 1,320,594, granted November 4, 1919, upon the application of Henry Windibank, of Croydon, England, for an improvement in "Apparatus for the Attachment of Electric Wires to Terminals," were erroneously issued to Arthur Taylor Treglown, trading as L. Taylor & Co., as owner of the entire interest in said invention, whereas said Letters Patent should have been issued to the inventor, said *Windibank*, and *Arthur Taylor Treglown, trading as L. Taylor & Co.*, jointly, said company being assignee of *one-half* interest only in said invention, as shown by the records of assignments in the Patent Office; and that the said Letters Patent should be read with this correction therein that the same may conform to the record of the case in the Patent Office.

Signed and sealed this 10th day of February, A. D., 1920.

[SEAL.]

M. H. COULSTON,
Acting Commissioner of Patents
